PUMP UNIT

John J. Orlich and Herman A. Orlich,
Philadelphia, Pa.

Application October 9, 1947, Serial No. 778,848

5 Claims. (Cl. 103—38)

1

Our invention is an improved pump unit for producing an hydraulic flow at a pressure and output which are variable at will during continuous running of the apparatus without varying the speed of the motive source.

In a preferred embodiment of our invention, a motive source, such as a constant speed electric motor and a speed reducer are axially aligned with one another at one side of a base adjacent to an end thereof, and a stroke regulator and pump cylinder and valve chest are aligned with one another on the opposite side of the base adjacent to the opposite end thereof. The electric motor and stroke regulator are aligned transversely of the base and the stroke regulator is pivotally connected with a crank rotatable by the stroke regulator and with a piston reciprocable in the pump cylinder.

The stroke regulator is preferably housed in a frame mounted on the base and having spaced walls and a top crosspiece. The frame has fulcrumed thereon a lever which preferably consists of a pair of L-shaped members having trunnions adjacent to the upper ends of the longer legs thereof and journalled in the upper portions of the frame walls. The shorter legs of the L-shaped members are pivotally connected, through a connecting rod, with a crank rotatable by the speed reducer to impart oscillations of constant stroke to the lever.

A shaft is journalled in the frame head, with its axis intersecting the axis of the lever, and includes a depending flexible section and a screw on which is suspended a head movable by the screw along and operatively connected with the lever, preferably by a spline connection formed by a slideway and slide. The head is pivotally connected, through a connecting rod, with the pump piston which is thereby reciprocated in a bore or chamber in the cylinder.

The flexible joint of the shaft permits the oscillation of the screw section thereof with the lever and the rotation of the screw during the oscillation of the lever and in any position thereof. The turning of the screw moves the head suspended thereon toward or from the axis of oscillation of the lever to vary the throw of the connecting rod and piston connected therewith.

The backward stroke imparted to the piston unseats a ball inlet valve confined between a perforated disk and slotted cage in an enlargement of the cylinder bore and fills the bore with liquid. On the forward stroke of the piston, the pressure reseats the inlet valve and unseats ball valves controlling efflux passages extending normally to the cylinder bore.

2

The principal and characteristic features of our invention, and the manner of making, constructing and using our improved pump unit will further appear from the accompanying drawings and the following description explaining the best mode in which we have contemplated applying such principles.

In the drawings Fig. 1 is a perspective view of an hydraulic pump unit embodying our invention; Fig. 2 is a perspective view of the pump unit taken from the end opposite that shown in Fig. 1; Fig. 3 is a part sectional, side elevation of the hydraulic pump unit shown in Figs. 1 and 2, with the pump piston and connected parts retracted; Fig. 4 is an exploded view of the component parts of the stroke regulator; Fig. 5 is a part sectional, side elevation similar to Fig. 3 but with the parts advanced 180° in their operating cycle; Fig. 6 is a vertical sectional view taken along the line 6—6 of Fig. 1; Fig. 7 is a vertical sectional view taken along line 7—7 of Fig. 6; Fig. 8 is an enlarged cross-sectional view taken along the line 8—8 of Fig. 2, showing the pump cylinder and check valve system.

10 The embodiment of our invention illustrated in the drawings embodies a base 1 on which are mounted the constant speed electric motor 2, speed reducer 3, stroke regulator frame 4 and pump 5.

15 The motor 2 is aligned with the speed reducer 3 and supplies, through a shaft 6, power for rotating the shaft 7 and crank 8.

20 The crank 8 is connected, through a connecting rod 9, with the stroke regulator mounted in the frame 4. The stroke regulator frame 4 is aligned, rectilinearly of the base, with the pump 5 and, transversely of the base, with the motor 2. The speed regulator is pivotally connected through the connecting rod 10, with the reciprocable head 11 of a piston 12 which is movable

25 through the packing 13 into the bore 14 of the pump cylinder 15.

25 The stroke regulator comprises a pair of L-shaped members 16 having the upper portions of their longer legs journalled on trunnions 17 projecting inwardly from the spaced walls or standards 18 of the frame 4. The members 16 thus form a lever 16—16 fulcrumed near its upper end on the upper portion of the frame 4.

30 The transverse and shorter legs of the members 16 are pivotally connected, through the pintle 19, with the end of the connecting rod 9, so that the lever 16—16 is oscillated a fixed distance proportional to the throw of the crank 8.

35 A shaft 20 has a reduced portion journalled in a boss 21 on the cross-piece 22 of the frame

40

4 and is rotatable by means of a handwheel 25 fixed thereto. An indicator ring 26, fixed to the shaft 20, rests on the boss 21, and indicates, with respect to a datum, the rotation of the shaft 20. A lock nut 27 is threaded on the shaft 20 to lock the shaft 20 against undesired rotation.

5 The shaft has a flexible section formed by a universal joint 28 and a threaded section or screw 29 depending therefrom.

A cross-head 30 is threaded on and suspended from the screw 29. The bifurcated end of the connecting rod 10 is journaled on cylindrical bearings of the cross-head 30 on opposite sides of the screw 29 and the reduced cylindrical ends of the cross-head are journaled in slides 31 slideable in slideways 32 formed in inner adjacent surfaces of the members 16. By loosening the nut 27 and rotating the wheel 25, the cross-head 30 and connecting rod 10 may be moved toward and from the axes of the trunnions 17 and thus change the stroke of the piston 12 to any desired degree during the operation of the apparatus. During the operation of the pump, the screw 29, lever 16-16 and rods 9 and 10 all oscillate about different axes. To slow or stop the operation of the pump, the head 30 may be moved toward or into alignment with the axis of the trunnions 17.

The cylindrical bore 14 has a flaring outer end 33 terminating in a threaded cylindrical seat 34 for a perforated disk 35 and a ferrule 36 containing an axial aperture 36' having an enlarged section for receiving a cage 37 having a concave valve seat 38 and a slotted cylindrical wall 39 for retaining a ball valve 40.

A plugged drain port 40' and discharge port 41 are drilled in the cylinder 15 so as to intersect the bore 14. The port 41 is controlled by a ball 42 seated in a cage 43 having a slotted cylindrical wall. The port 41 discharges into a chamber 44 closed by a plug 45 having a stem 46 limiting the movement of the ball 42. The chamber 44 discharges through a passage 47 controlled by a ball valve 42' and cage 43' similar to the parts 42 and 43. The passage 47 discharges through a chamber 44' and passage 47' to the external fitting 48. The chamber 44' is closed by a plug 45' similar to the plug 45.

It will be understood that the amount of liquid pumped and the pressure at which it is ejected is governed by the throw of the piston 12 in the bore 14 and that the throw of the piston is controlled by the stroke regulator.

Each revolution of the crank 8 is translated into linear motion by the pitman 9 which oscillates the lever 16-16 about the trunnions 17, a given amount in each direction. The throw transmitted by the lever 16-16 to the piston 12 varies directly with the distance between the head 30 and trunnions 17.

To increase the stroke of the piston 12, the handwheel 25 and screw 24 are turned so as to increase the distance from the trunnions 17 to the head 30. The throw will be at a maximum when the head 30 is at the greatest distance from the fulcrum provided by the trunnions 17. Conversely, to decrease the throw the head 30 is moved upwards towards the trunnions 17 by means of the screw 24. When the head 30 is in line with the trunnions 17, the throw of the connecting link 10 and piston 12 will be zero. The universal coupling 21 connecting the handwheel 25 and screw 24 permits the adjustments of the head 30 to be made at any position of the lever 16-16 or while the pump is running. When the desired adjustment has been completed, the

head 30 is locked in position by turning the lock nut 27.

During the pumping stroke of the piston 12, the ball valve 40 is tightly seated, whereas the ball valves 42 and 42' are unseated and the fluid is discharging around the balls and through the passages controlled thereby. When the piston 12 begins to reverse its motion, a partial vacuum is created in the bore 14. Whereupon the ball 42 and 42' will fall and seat and the ball 40 will be drawn from its seat toward the apertured washer 35. The unseating of the ball checks 36 permits the fluid to flow or be drawn from the inlet pipe and fill the bore 14. As the piston completes the suction stroke, the bore 14 is substantially filled. As soon as the piston 12 moves forward again, pressure will be exerted on the fluid by the piston which will cause the ball 40 to be seated. Increase of pressure will tend to seat the ball 40 more firmly. As soon as the pressure in the bore 14 is greater than that in the chamber 44, the ball 42 will be unseated, allowing pressure to be exerted upon the ball check 42'. As soon as the pressure in the bore 14 and chamber 44 exceeds that in the chamber 44', the ball check 42' will be lifted, permitting the fluid to pass to the outlet port 48.

The twin ball checks 42 and 42' permit pressure to be built up in two distinct stages resulting in a final discharge pressure through the outlet port 48 of substantial uniformity. As the piston 12 comes to the end of the pressure stroke, the ball check 42' will reseat at the first indication of a diminution of pressure, whereas the inner ball check 42 will not reseat until a substantially greater diminution of pressure has taken place. This results in both checks sharing the pressure loss, thereby permitting greater total pressure than would otherwise be possible with a single ball check as well as providing a greater margin of safety in providing against leak backs to the cylinder.

It will be understood that the clearance between the periphery of the cylindrical piston 12 and the inner cylindrical surface of forward portion of the bore 14 (e. g. between the passage 41 and the flare 33) is sufficient to permit flow of liquid therebetween when the piston 12 is advanced beyond the passage 41.

Having described our invention, we claim:

1. A pump unit comprising a motive member including a driving means and a speed reducing means, a piston member, a stroke regulator comprising a fulcrumed oscillatory lever with which said motive member and piston member are operatively connected, and means for shifting the point of connection of one of said members to the lever relatively to the fulcrum of the latter including alignment of said point of connection and said fulcrum, said shifting means including a shaft having a threaded section operatively connected with said last named member and a flexible joint permitting movement of said threaded section with said lever.

2. A pump unit comprising a piston chamber, a piston reciprocal in said piston chamber, a frame, a stroke regulator housed within said frame, said stroke regulator including a pair of L-shaped members having trunnions adjacent to the upper ends of the longer legs thereof and journaled in the upper portions of said frame, a head operatively connected with said longer legs and movable within and shielded by the same, a connecting rod connecting said piston and head, a rotatable shaft journaled

in the head of said frame and having a threaded section operatively connected with said head to shift it along said longer legs, said shaft including a flexible joint between said frame and head, a motive member including a rotatable crank, and a connecting rod connecting said crank and the shorter legs of said L-shaped members.

3. A pump unit comprising a base, a motor and speed reducer in tandem along one side of the base adjacent to one end thereof, a stroke regulator and pump in tandem along the other side of the base adjacent to the opposite end thereof, said motor and stroke regulator being substantially in alignment with the shorter axis of said base, and a crank and connecting rod aligned with said stroke regulator and said pump and connecting said speed reducer and said stroke regulator.

4. A pump unit comprising a base, a motor and speed reducer in tandem along one side of the base adjacent to one end thereof, a stroke regulator and pump in tandem along the other side of the base adjacent to the opposite end thereof, said motor and stroke regulator being substantially in alignment with the shorter axis of said base, a crank and connecting rod aligned with the said stroke regulator and said pump and connecting said speed reducer and said stroke regulator, and a substantially non-flexible coupling aligned with and connecting said motor and said speed reducer.

5. A pump unit comprising a base, a frame having spaced walls mounted on said base, a pair of complementary oscillatory L-shaped levers fulcrumed in said walls and having guide-

ways extending lengthwise along the longer legs of the adjacent surfaces of said L-shaped levers, a top cross-piece on said frame, a head movable along said guideways, a shaft rotatable within said top cross-piece for shifting said head along said guideways relatively to the fulcrums of said L-shaped levers including alignment of said head with said fulcrum, a power source operatively connected with one end of said levers, and a connecting rod connecting a piston and said head.
